UNITED STATES PATENT OFFICE.

JOHN H. HUNT, OF DAYTON, OHIO, ASSIGNOR TO THE DAYTON ENGINEERING LABORATORIES COMPANY, A CORPORATION OF OHIO.

IGNITION SYSTEM.

Application filed November 11, 1918. Serial No. 261,945.

To all whom it may concern:

Be it known that I, JOHN H. HUNT, a citizen of the United States of America, residing at Dayton, county of Montgomery, 5 State of Ohio, have invented certain new and useful Improvements in Ignition Systems, of which the following is a full, clear, and exact description.

This invention relates to ignition systems 10 for internal-combustion or explosion engines.

Among the objects of the invention is the provision of an ignition system including a plurality of sparking circuits which are operated in such a manner as to provide a series of sparks at recurring unequal intervals, that is, the intervals between the successive sparks are unequal, while alternate intervals are equal. Such a sequence of 15 sparks will be termed a non-symmetrical sequence.

The invention also provides means for distributing all of the sparking impulses created in the manner referred to in non- 5 symmetrical sequence to suit the requirements of a particular type of internal-combustion engine.

Other and further objects and advantages 10 of the present invention will be apparent from the following description, reference being had to the accompanying drawings, wherein preferred embodiments of the present invention are clearly shown.

In the drawings:

35 Fig. 1 is a wiring diagram showing certain elements which are included in the present invention.

Fig. 2 is a longitudinal sectional view of a timing and distributing unit which includes certain of the elements shown in 40 Fig. 1.

Fig. 3 is a wiring diagram showing a modified form of the invention.

Fig. 4 is a cross sectional view taken on 45 the line 4—4 of Fig. 3.

Fig. 5 is a wiring diagram showing a still further modified form of the invention.

Referring to Fig. 1, 20 and 21 designate as a whole, ignition coils having primary windings 22 and 23 which are connected with a battery 24 having a ground connection 25. The primary coil 22 is connected

by means of a wire 26 with a terminal 27 which is mounted on a timer cup 28. The primary winding 23 is connected by means 55 of wire 29 with terminal 30, likewise mounted on the timer cup 28. The cup 28 is provided with a base 31 upon which are mounted breaker arms 32 and 33, said arms being insulated from the base 31. Arms 32 and 33 60 carry contacts 34 and 35 respectively, which engage with stationary contacts 36 and 37 respectively, which are mounted upon upturned ears formed integrally with the base 31. The terminal 27 is connected by means 65 of a spring 38 with the arm 32. Said spring 38 serves as an electrical connection and also to maintain the contacts 34 and 36 normally in engagement. Spring 39, connecting the terminal 30 with the arm 33, functions in 70 the same manner as the spring 38.

The timer cup 28 is formed integrally with a housing 40 which supports an engine driven shaft 41. Said shaft 41 is cuffed at its upper end to receive the slotted 75 end of a stub shaft 42. Shaft 42 carries a disc 43 upon which are mounted centrifugal weight members 44, only one being shown. The stub shaft 42 is recessed at its upper end to provide a bearing for cam shaft 45. 80 Said shaft 45 is journaled upon the base 31 and carries the timer cam 46 and distributing rotor 47. Each weight member 44 is provided with an arm 48 which engages an outwardly extending arm 49 carried by 85 the cam shaft 45. In this manner a driving connection between the stub shaft 42 and the cam shaft 45 is effected. Springs, not shown, serve normally to maintain the weight members 44 in their innermost position toward the shaft 45.

The shaft 41 is provided with diagonal slots, one being shown at 50, and a pin 51, carried by the grooved sleeve 52, extends through the diagonal slots 50 and through 95 the slotted end of the shaft 42. By means of the pin 51, a driving connection is effected between the shaft 41 and shaft 42. The shaft 42 may be displaced angularly with respect to the shaft 41 by causing the sliding of the grooved collar 52 by means of the arm 53, which may be operated manually by a connection with the shaft 54 upon which the arm 53 is mounted. The automatic dis-

placement of the cam shaft 45 with respect to the shaft 41 is effected by the action of the centrifugal members 44 in a well known manner.

5 The distributor head 60 comprises a shell 61 which is mounted upon the timer cup 28. A conducting ring 62 is mounted upon the shell 61. The head 60 comprises also a cup shaped member 63 which is located within 10 the shell 61 and rests upon the ring 62. Said member 63 is provided with a center contact 64 and a series of stationary contacts 65 arranged in a circular fashion, each of said contacts 65 being connected with the 15 spark plugs of an engine not shown. The rotor 47 is provided with a contact plate 66 which makes an electrical connection between the center contact 64 and brush 67 carried by the rotor 47. The rotor 47 is provided with a brush 68 which effects an electrical connection between the ring 62 and a brush 69 also carried by the rotor. Brushes 67 and 69 are adapted to contact 20 with the stationary contacts 65 and, to distribute 25 sparking impulses thereto.

The ignition coil 20 is provided with a secondary winding 72 cooperating with the primary winding 22, and said winding 72 is connected by means of wire 71 with the 30 center contact 64 represented by the dot in Fig. 1. The ignition coil 21 is provided with a secondary winding 73 cooperating with primary winding 23, said winding 73 being connected, by means of wire 74, with 35 the ring 62. Condensers 75 and 76 are connected in parallel with the breakers 33 and 32 respectively. Condensers 75 and 76 may be enclosed within a casing 77 which is attached to the cover 78 of the housing 40 as 40 shown in Fig. 2.

Referring to Fig. 1, it will be noted that the breaker arms 32 and 33 are not placed diametrically opposite with respect to the cam 46, and that the brushes 67 and 69 of 45 the rotor 47 are not placed diametrically opposite with respect to the axis of the rotor.

In Fig. 1, line 32* is a line intersecting the cam center and the point of contact of the cam periphery and the rubbing block 32* of 50 breaker arm 32. Line 33* is a line intersecting the axis of cam 46 and the point of contact of the cam periphery and rubbing block 33* of breaker arm 33. For sake of convenience these lines 32* and 33* will be referred 55 to in the specification and claims as the "center lines" of the breaker rubbing blocks. In the embodiment shown in Fig. 1, the angle between these lines is 22.5°. The line 67* intersects the axis of rotor 47 and the 60 center of brush 67, and the line 69* intersects the axis of rotor 47 and the center of brush 69. These lines 67* and 69* will be referred to in the specification and claims as 65 the "center lines" of the distributing conductors. In the embodiment shown in Fig.

1, the angle between these lines is 22.5°. This construction and arrangement permits the alternate operation of the breaker arms 32 and 33 by means of a cam 46 to break, alternately, the primary circuits in the ignition coils 20 and 21. The intervals between the breaking of these primary circuits measured in angles of rotation of the cam 46 will be 22.5° and 67.5° alternately. By reason of the non-symmetrical arrangement of the brushes 67 and 69 upon the rotor 47, the 70 sparking impulses which have been produced in non-symmetrical sequence by means of the operation of the cam upon the breakers, will be distributed in like manner 75 in non-symmetrical sequence in the various spark plugs of the engine. Where the crank shaft of the engine operates at twice the speed of the cam shaft 46, sparks will be delivered to the engine at intervals of 45° and 80 135° alternately with respect to the engine crank shaft. This particular firing order 85 will be suitable for an eight cylinder engine of the 45° V-type with crank throws at 180°. 90

It is evident that these angles between 95 the center lines of cam rubbing blocks and between the center lines of distributing conductors will not be the same for all V-type engines but will vary according to the number of cylinders, the angle between the rows 100 or banks of cylinders and as to whether the timer cam is driven at engine speed or at one-half engine speed.

The number of coils and breakers in any 105 case will equal the number of rows or banks of cylinders. This number is generally two. If V equals the angle between the cylinder blocks and the cam speed is one-half engine speed, then the angle between the center lines of the two cam rubbing blocks is $\frac{V}{2}$,

and the number of cam lobes is $\frac{N}{2}$, N being 110 the number of engine cylinders. Obviously, if the cam speed equals engine speed then the angle between the center lines of rubbing blocks will be V ; and the number of cam lobes is $\frac{N}{4}$.

Since each distributing brush makes a 115 complete cycle every engine cycle, it is evident that the rotor 47 must rotate at one-half engine speed for a four stroke cycle engine. The distributor head will have N 120 stationary contacts equally spaced and the angle between each contact will be 360° divided by N . Each distributing brush or conductor distributes to alternate stationary contacts, hence the angle between the center 125 lines of distributing conductors equals

$$\frac{360^\circ \cdot V}{N - 2}$$

Referring to Figs. 3 and 4, it will be noted 130 that the arrangement of the breakers with

respect to the timer cam is identical with that shown in Fig. 1. In this modification feature the stationary contacts are not all arranged upon the same circle with respect to the axis of the rotor.

In Figs. 3 and 4 numeral 100 designates the modified form of distributor head which is provided with a ring 101 of conducting material. This ring 101 is connected by means of a wire 74 with the secondary winding 73 of the ignition coil 21. The head is provided with a center contact 102 which is connected by means of the wire 71 with the secondary winding 72 of the ignition coil 20. 105 designates a modified form of distributor rotor which is provided with a contact 106 which cooperates with the center contact 102. Contact 106 is connected by means of a conductor 107 with a brush 108. 20 Brush 108 is arranged to cooperate with the outer-row of stationary distributor contacts 109. The rotor 105 is provided with a brush 110 which is arranged to contact with the ring 101, and is connected by means of 25 a conductor 111 with a brush 112. Brush 112 is arranged to cooperate with the inner-row of stationary distributor contacts 113.

In the modification just described, and shown in Figs. 3 and 4, the operation of the timer is the same as that of the timer shown in Fig. 1. Sparking impulses are created in ignition coils 20 and 21 alternately and these impulses are conducted to the center contact 102 and the ring 101, respectively. From the ring 101 and the center contact 102, current will be conducted to the brushes 112 and 108 respectively, by means of which the impulses are distributed alternately to one of the inner-row of stationary contacts 113 and 40 to one of the outer-row of stationary contacts 109. By virtue of the construction and arrangement described the interval between consecutive sparks will be 45° and 135° alternately with respect to the turning of the 45 crank shaft. Thus, the modified form of embodiment of the invention shown in Fig. 3 will produce the same result as the first form shown in Fig. 1.

Another type of engine having non-symmetrical firing order is the 45° V-type eight cylinder engine having cranks at 90° . The intervals between successive sparks of this type of engine may be as follows: 90° , 90° , 90° , 135° , 90° , 90° , 90° , and 45° . In order 55 to provide ignition suitable for this type of engine a non-symmetrical cam 120 is provided, as shown in Fig. 5, to co-operate with the breaker arms 32 and 33. By means of the cam 120 the breaker arm 32 will be 60 operated to break the circuit in the induction coil 20 four times in succession, and then the breaker arm 33 will be operated four times in succession to break the primary circuit of the ignition coil 21. By locating the 65 arms 32 and 33 with respect to the cam 120

so that the angle with respect to the cam shaft included between the pivot points of the arms 32 and 33 is 157.5° , sparking impulses in the order referred to will be created. The secondary winding 73 is connected by means of a wire 74 with an arcuate conducting strip 121. The secondary winding 72 is connected by means of a wire 71 with the center contact 64, and the rotor 122 is provided with a brush 123 which engages the strip 121 and conducts current to a brush 124. The rotor 122 is provided with a conducting strip 125 which conducts current from the center contact 64 to the brush 126. The cam 120 will operate the arm 32 to open the contacts 34 and 36 four times in succession whereby to create four successive impulses in the ignition coil 20. These impulses will be distributed by means of the brush 126 to the stationary contacts 127, 128, 129 and 130. The intervals between these consecutive sparks will be 90° with respect to the engine crank shaft. Upon a 135° rotation of the crank shaft after the distribution to the contact 130, the cam 120 will 90 operate the arm 33 four times in succession to cause the opening of contacts 35 and 37, whereby to create four consecutive impulses in the ignition coil 21. Upon a 135° rotation of the crank shaft the contact 130, brush 124 will distribute sparking impulses to the contacts 131, 132, 133, and 134. The intervals between the distribution of these spark plugs will be 90° with respect to the engine crank shaft. Upon a 45° of the crank shaft 100 after the last opening of the contacts 35 and 37 the cam 120 will begin to operate upon the breaker arm 32, and at the same time the brush 127 will be in position to distribute to the stationary contact 34. In this 105 manner the sparking impulses will be created in the order referred to, to supply the correct ignition for an eight cylinder 45° V-type engine having crank throws at 90° .

While the embodiments of the invention 110 herein disclosed are applicable to certain types of combustion engines, it is to be understood that suitable ignition could be supplied to other types of engines having non-symmetrical firing intervals, by varying the 115 angular disposition of the breakers with respect to the cam shaft or by varying the shape of the cam, also by making corresponding changes in the angular disposition of the distributing brushes carried by the 120 rotor.

In the claims, the term "symmetrical cam" means a cam having equally spaced lobes of the same dimensions; and the term "non-symmetrical cam" means a cam having lobes 125 which are not all equally spaced.

While the forms of mechanism herein shown and described constitute preferred forms of embodiments of the invention, it is to be understood that other forms might be 130

adopted, all coming within the scope of the claims which follow.

I claim—

1. In an ignition system for multi-cylinder internal-combustion engines having non-symmetrical firing sequence, the combination with a plurality of coils each serving to supply sparking impulses to a plurality of cylinders; of means for energizing and discharging said coils alternately and in non-symmetrical sequence; and distributing means including a single head having a plurality of stationary contacts connected respectively with the engine spark plugs, and rotatable distributing conductors each connected with an ignition coil, said conductors and said contacts being arranged to effect non-symmetrical distribution of the sparking impulses.
2. In an ignition system for multi-cylinder internal-combustion engines having non-symmetrical firing sequence, the combination with a plurality of coils each serving to supply sparking impulses to a plurality of cylinders; of means for energizing and discharging said coils alternately and in non-symmetrical sequence; and distributing means including a head having a plurality of stationary terminals connected respectively with the engine spark plugs, said terminals having their respective contacting surfaces located in the same plane, and including a rotor having a plurality of distributing conductors cooperating with said contacts, each conductor being connected with an ignition coil, said conductors and said contacts being arranged to effect non-symmetrical distribution of sparking impulses.
3. In an ignition system for multicylinder internal-combustion engines having non-symmetrical firing sequence, the combination with a plurality of coils each serving to supply sparking impulses to a plurality of cylinders; of means for energizing and discharging said coils alternately and in non-symmetrical sequence; and distributing means including a plurality of stationary contacts spaced at equal angles, and movable distributing conductors each connected with a coil, the center lines of said conductors being obliquely disposed whereby to effect non-symmetrical distribution, each conductor distributing to alternate stationary contacts.
4. In an ignition system for multicylinder internal-combustion engines having non-symmetrical firing sequence, the combination with a plurality of coils each serving to supply sparking impulses to a plurality of cylinders; a symmetrical engine driven cam; a plurality of breakers having cam rubbing blocks the center lines of which are obliquely disposed so as to be operated by said cam in non-symmetrical sequence; and distributing means including a plurality of stationary contacts spaced at equal angles, and movable distributing conductors each connected with a coil, the center lines of said conductors being obliquely disposed whereby to effect non-symmetrical distribution, each conductor distributing to alternate stationary contacts.
5. In an ignition system for multicylinder internal-combustion engines having non-symmetrical firing sequence, the combination with a plurality of coils each serving to supply sparking impulses to a plurality of cylinders; of means for energizing and discharging said coils alternately and in non-symmetrical sequence; distributing means including a plurality of stationary contacts spaced at equal angles, and movable distributing conductors the center lines of which are obliquely disposed whereby to effect non-symmetrical distribution; means for connecting one coil with one of the conductors including a stationary center contact connected with said coil and a movable contact plate connecting said conductor with said center contact; and means for connecting the other coil with the other distributing conductor including a stationary conducting spring connected with said coil and a movable brush connecting said ring with said other conductor.
6. In an ignition system for four cycle internal-combustion engines of the V-type having N cylinders, V denoting angle in degrees between the rows of cylinders, the combination with two ignition coils; of a current source; timing means for energizing and discharging said coils alternately and in non-symmetrical sequence; and distributing means including N stationary contacts spaced at equal angles and two movable distributing conductors the center lines of which are obliquely disposed at an angle of $\frac{360}{N} - \frac{V}{2}$ degrees, each conductor being connected with one of said coils.
7. In an ignition system for four cycle internal-combustion engines of the V-type having N cylinders, V denoting angle in degrees between the rows of cylinders, the combination with two ignition coils; of a current source; a timer including a symmetrical cam having $\frac{N}{2}$ lobes and arranged to be driven at one-half engine speed, and including two breakers having rubbing blocks the center lines of which are obliquely arranged at $\frac{V}{2}$ degrees, and each breaker cooperating with the current source and one of the coils; and distributing means including N stationary contacts spaced at equal angles and two movable distributing conductors the center lines of which are obliquely disposed at an angle of $\frac{360}{N} - \frac{V}{2}$ degrees, each conductor being connected with one of said coils.

lines of which are obliquely disposed at an angle of

$$\frac{360}{N} \text{ V}$$

5

degrees, each conductor being connected with one of said coils.

8. In an ignition system for a four cycle internal-combustion engine of the V-type having eight cylinders, the angle of the V being 45° , the combination with two ignition coils; of a current source; a timer including a symmetrical four-lobe cam driven at one-half engine speed, and including two breakers having rubbing blocks the center lines of which are obliquely arranged at 22.5° , and each breaker cooperating with the current source and one of the coils; and distributing means including eight stationary contacts spaced at equal angles and two movable distributing conductors the center lines of which are obliquely disposed at 22.5° , each conductor being connected with one of said coils.
9. In a distributor rotor for igniton systems of internal-combustion engines of the V-type, a non-conducting rotatable support, two distributing conductors arranged on said support at the same distance from the axis thereof and having their center lines obliquely disposed, said conductors being arranged to distribute alternately to a circular row of stationary distributor contacts, a contact plate for collecting current at the

axis of said rotor and for conducting to one of said conductors, and a collecting brush connected to the other conductor and arranged to collect current from a stationary cylindrical band.

10. In an ignition system for multicylinder internal-combustion engines having non-symmetrical firing sequence, the combination with a plurality of coils each serving to supply sparking impulses to a plurality of cylinders; of means for energizing and discharging said coils alternately and in non-symmetrical sequence; and distributing means including a head carrying a plurality of stationary contacts spaced at equal angles and arranged in the same plane, a center contact, a conducting ring arranged in a plane parallel to the plane of said stationary contacts, and a rotor carrying two distributing conductors obliquely disposed to provide distribution by each conductor to alternate stationary contacts and all together in non-symmetrical sequence, said rotor carrying a collecting brush arranged to contact with said ring and connected with one of said distributing conductors, and said rotor carrying a center brush contacting with said center contact and connected with the other distributing conductor.

In testimony whereof I affix my signature.
JOHN H. HUNT.
